United States Patent Office.

GEORGE W. MILLER, OF WEST MERIDEN, CONNECTICUT.

Letters Patent No. 80,756, dated August 4, 1868.

IMPROVEMENT IN TOOL FOR MENDING BELTS.

The Schedule referred to in these Letters Patent and making part of the same.

TO ALL WHOM IT MAY CONCERN:

Be it known that I, GEORGE W. MILLER, of West Meriden, in the county of New Haven, and State of Connecticut, have invented a new and useful Improved Knife and Tool for Mending Belts; and I do hereby declare that the following is a full, clear, and exact description thereof, reference being had to the accompanying drawings, making a part of this specification, and to the letters of reference marked thereon, in which—

Figure 1 is a perspective view of my invention.

Figure 2 is a front view, showing the knife-blade open.

Figure 3 is a longitudinal section through the line A B of fig. 2.

Figure 4 is a back view of the knife or tool.

Figure 5 is a plan view of the bolt, and

Figure 6 is a side view of the same.

The nature of my invention consists in the construction of a knife and tool for mending belts, whereby the different articles generally used for that purpose are arranged in one handle, and in convenient form to be carried in the pocket; and it also consists in the arrangement and construction of a bolt in a handle, for the purpose of securing the knife-blade, or other article to be used, either open or shut, so that said knife-blade or other implement will neither shut of itself in using, nor open of itself in the pocket.

As generally constructed, belt-awls and belt-punches are made separate and apart from each other, and when it becomes necessary for a belt to be mended, it often happens that neither the punch nor the awl can be found, some one else having them in use, or they may have been left out of their accustomed place. This is quite often the case, and a long and generally vexatious search is the result, which has been, perhaps, participated in by more than one employee. Such search is, of course, more or less expensive to the proprietors or company, as more or less valuable time is wasted in the search, and, of course, the machines, whose belts need mending, have to be idle until the belt is mended.

My invention obviates any necessity for such waste of time and money, as my invention can be safely and conveniently carried in the pocket, while it is convenient and effective in its operation.

To enable others skilled in the art to make and use my invention, I will proceed to describe its construction and mode of operation.

I take a suitable piece of metal, which may be in the sheet, and form it by any suitable means into a case, having a back, a , and two sides, $a^1 a^2$, or, if preferable, said case may be made of cast metal instead of making it of metal in the sheet. I prefer the latter, however.

Into one end of this metallic case, I fit a suitable piece, b , which may be of wood, metal, hard rubber, or of any other desirable material, said piece b having a socket, s , extending lengthwise therein, into which is inserted a spring, t . A slot, r , is made in the back, a , of the metallic case, through which slot is inserted or passes the neck of the knob n , which is secured to the bolt m in any suitable manner.

This knob n may be made of any desirable shape and size, as the fancy may dictate. The bolt, m , is made of a sufficient width and thickness at the end h to occupy the space between the ends $o o o$ of all the implements, and the back, a , of the metallic case; or, in other words, the end, h , of the bolt is of a width nearly equal to the inside width of the metallic case at the end where the tools are secured to the case or handle, and of a thickness nearly equal to the space between the heel o of the blade or tool and the back, a , of the case. To reduce the weight and save expense, I make the other portion of the bolt m more narrow, and with a shoulder at v , the portion quite near the end being smaller still. This small portion is inserted into the spiral spring t in the socket s , said spring bearing against the shoulder v , and operating to push the bolt m out of and away from the socket s .

The awl, d , may be of any desirable form in its cross-section usually given to belt-awls, pointed at one end, having a shoulder and heel o at the other end, like that of a knife-blade in a common pocket-knife.

The knife-blade e is of the same form throughout as that given to common pocket-knife blades, and needs no particular description, the drawing showing clearly its construction.

The punch, *e*, is semicircular at one end, the point or end having a sharp cutting-edge, and also the edges *f* *f'* being made sharp, the other end, *o*, having a shoulder and heel of the same form as that of the knife *c* and awl *d*.

The end, *o*, of the knife *c*, awl *d*, and punch *e*, each has a small tube therein, through which passes a small pivot, *i*, which also passes through each side of the metallic case, near its end, and said pivot is headed down slightly at each end to secure it in place.

The several tools swing in and out of this case upon the pivot *i*, like the blades of a common pocket-knife.

A small space, *l*, is left in each side of the case, for convenience in seizing the particular tool wanted in opening it.

Its operation is as follows: When it is desired to use either one of the implements, all of them being shut, the bolt *m* is forced back into its socket *s* in the piece *b*, by pressing the knob *n* back towards said piece *b*. Any one of the implements is then free to be opened, and when open, the pressure against the knob *n* is removed, when the spring *s* forces the bolt forward, so that its end *h* fills the space between the heel *o* of the implement and the back of the case, which operation of the bolt *m* securely locks the implement open, so that it will not shut in the hand while using. The same operation of the bolt *m* permits the implement to be closed.

As this bolt is much cheaper in its manufacture than the back-spring of common pocket-knives, it is evident that pocket-knives may be made with advantage, as herein described, having a metallic case and locking-bolt instead of the common handle and back-spring, as now made; the use of such knives being safer by the employment of a locking-bolt, herein described.

Instead of having the implements swing upon the pivot *i*, I might make the handle hollow or tubular, and, by the proper arrangement of springs and locks, cause the implements to shoot out endwise, as they are wanted; but I prefer the construction hereinbefore described.

Having thus described my invention, what I claim as new, and desire to secure by Letters Patent, is—

1. The bolt, *m*, with its spring *t*, in combination with the punch *e* and awl *d* of a belt-mending implement, or the blades of pocket-cutlery, when constructed and operating substantially as herein described, and for the purposes specified.
2. The punch *e*, blade *c*, and awl *d*, or any two of them, when secured in one handle for pocket-use, substantially as herein described, and for the purposes specified.
3. A belt-punch, having the sharp edge *f* and cutting-point *f'* at one end, and the shoulder and heel *o* at the other end, and secured in a handle by means of a pivot, *i*, substantially as herein described and set forth.

GEORGE W. MILLER.
